UNITED STATES PATENT OFFICE

148,408

DESIGN FOR A WALL VASE

Boyd W. Corwin, Orange, Calif.

Application May 8, 1947, Serial No. 138,910

Term of patent 3½ years

(Cl. D29—28)

To all whom it may concern:

Be it known that I, Boyd W. Corwin, a citizen of the United States, residing at Orange, in the county of Orange and State of California, have invented a new, original, and ornamental Design for Wall Vase, of which the following is a specification, reference being had to the accompanying drawing, forming part thereof.

Fig. 1 is a top elevational view;
Fig. 2 is a front elevational view;
Fig. 3 is a bottom elevational view;
Fig. 4 is a side elevational view;
Fig. 5 is a side elevational view; and
Fig. 6 is a back elevational view of a wall vase showing my new design.

I claim:

The ornamental design for a wall vase, as shown.

BOYD W. CORWIN.
